NO. 12,834

MARCH 28, 1882

UNITED STATES PATENT OFFICE.

GEORGE S. BARKENTIN, OF OCEANUS, NEW YORK, ASSIGNOR TO P. & F. CORBIN, OF NEW BRITAIN, CONNECTICUT.

DESIGN FOR A BRACKET.

SPECIFICATION forming part of Design No. 12,834, dated March 28, 1882.

Application filed July 1, 1881. Term of patent 14 years.

To all whom it may concern:

Be it known that I, GEORGE S. BARKENTIN, a citizen of the United States, residing at Oceanus, in the county of Queens and State 5 of New York, have invented and produced a new and original Design for Brackets, reference being had to the accompanying drawing, forming part thereof, which represents the design in perspective.

10 The leading features of my design consist, first, of the upright and horizontal bars parallel to the back and arm of the bracket, and a quadrant-shaped brace at the inside corner of said bars; and, second, in the further configuration of the bracket.

A represents the back, and B the arm extending therefrom, as in ordinary brackets. Parallel with the back A is a vertical bar, C, and parallel to the arm B is a horizontal bar, 20 D. These bars are connected to the back and arm by suitable intermediate work, hereinafter more fully described. A quadrant-shaped brace, E, is placed in the inside corner formed at the junction of the bars C and D. This 25 quadrant-shaped brace and the intermediate work between the bars and the back and arm may be of any pleasing design, so far as the first part of my invention is concerned; but I prefer to connect the lower end of the bar C to the back A by a curved bar, a, and horizontal bar b. The space inclosed by said bars a b and the back is filled in and ornamented by leaflets on a roughened and sunken ground. In the corner of the back and arm there is a filled 30 square, the same being bordered on two sides by bars c d, which are in line with the bars C D. The surface of this square is ornamented by a fan-shaped figure, from which leaflets ex-

tend on a roughened and sunken ground. The quadrant-shaped brace is ornamented in imitation of a fan. Between the bar D and the arm B there is a second parallel bar, F, and interwoven curved bars extend from bar D to arm B. The outer end of bar D is connected to arm A by a curved bar, e. The space inclosed by the back A and bars d C b has an ornamented panel, G, supported by short bars, so as to be surrounded by open-work.

I claim—

1. The design for a bracket herein shown and described, the same consisting essentially of the bars C D, parallel respectively to the back and arm and connected to each, and a quadrant-shaped brace, E, extending from the bar C to the bar D.

2. The design for a bracket herein shown and described, the same consisting of the bar C, parallel to the back, the bars d b, extending transversely thereto, and the inclosed ornamental panel G, surrounded by open-work.

3. The design for a bracket herein shown and described, the same consisting of the bars C D c d, parallel respectively to the back and arm, the quadrant-shaped brace, and the fan-shaped ornament at the inside corner of the bars c d.

4. The design for a bracket herein shown and described, the same consisting of the bars D and F, parallel to the arm A, the curved bar e at the outer end, and the interwoven curved bars.

GEORGE S. BARKENTIN.
